CLAIM

The ornamental design for a monitoring module, as shown
and described.

DESCRIPTION

FIG. 1 is a top front perspective view of a monitoring module;
FIG. 2 is a bottom rear perspective view of the monitoring
module;

FIG. 3 is a front view of the monitoring module;
FIG. 4 is a rear view of the monitoring module;
FIG. 5 is a top view of the monitoring module;
FIG. 6 is a bottom view of the monitoring module;
FIG. 7 is a left side view of the monitoring module; and,
FIG. 8 is a right side view of the monitoring module.
The broken lines in the drawings show the environment in
which the design is associated but form no part of the claimed
design.
